UNITED STATES PATENT OFFICE.

FRED C. FANTZ, OF PORT ARTHUR, TEXAS, ASSIGNOR TO THE TEXAS COMPANY, OF NEW YORK, N. Y., A CORPORATION OF TEXAS.

BARREL-PAINTING MACHINE.

Application filed November 24, 1920. Serial No. 426,215.

To all whom it may concern:

Be it known that I, FRED C. FANTZ, a citizen of the United States, residing in Port Arthur, in the county of Jefferson and State of Texas, have invented certain new and useful Improvements in Barrel-Painting Machines, of which the following is a specification.

This invention relates to apparatus for painting or applying liquid coatings to barrels, casks and similar articles.

One object of the invention is to provide a durable and efficient mechanism that is power operated and capable of painting barrels in large quantities in a continuous and rapid manner.

Another object of the invention is to provide suitable elevating mechanism whereby the barrels, after having been painted may be discharged in an upright position in order that the painted surfaces may not be soiled or disfigured while being conveyed from the apparatus.

Other objects and advantages of my invention will become apparent from the following detailed description thereof.

Referring to the drawings:

Figure 1 is a side elevation of an apparatus arranged in accordance with the invention and constituting an embodiment thereof.

Figure 2 is a plan view taken on the line 2—2 of Figure 4.

Figure 3 is a sectional elevation taken on the line 3—3 of Figure 2.

Figure 4 is a sectional elevation taken on the line 4—4 of Figure 2.

Figure 5 is a plan view of the carriage or elevating frame.

Figure 6 is a sectional elevation taken on the line 6—6 of Figure 5.

Figure 7 is a partial elevation showing the rotatable drum.

Figure 8 is a longitudinal section taken on the line 8—8 of Figure 7 but drawn to a larger scale.

Figure 9 is a view in detail of a movable sprayer member.

Figure 10 is a cross section of the sprayer taken on the line 10—10 of Figure 9.

In the drawings like parts are designated by the same reference character throughout all the figures.

The apparatus requires suitable support-

ing framework which in the form of the invention illustrated comprises a pair of I beams 10 upon which is positioned a horizontally disposed frame 11 which supports a plurality of uprights 12 provided with such crosspieces and braces as may be necessary to form a substantial supporting structure.

At the base of the machine and located beneath the barrel in its position during the painting operation is a paint pan 13. The pan may be formed with an inclined bottom, as illustrated, and a suction pipe 14 connected to a pump 15 is arranged to withdraw liquid from the pan. The pump has an outlet line 16 which is adapted to conduct paint to the spraying mechanism. The pipe 16 preferably terminates in a plurality of branch lines 17 through which the paint enters the spray pipe 18. The pump may also have a branch line 16^a leading to a suitable source of paint.

Any suitable spray pipe may be employed in carrying out the invention. Difficulty has, however, been experienced in the past in the construction of a spraying means for paint that will not clog up due to the partial drying of the paint, the presence of flaky materials in the paint and sometimes foreign substances that tend to seal the spraying perforations. I have designed a novel form of construction by which these difficulties have been obviated, the mechanism comprising a spray pipe having hinge connected sections which when open enables the pipe to be flushed and the perforations kept clean.

In the type of construction illustrated in detail in Figures 9 and 10 the sprayer has a base plate 19 to one side of which is rigidly secured a plate 20. At each end are plates 21 and a movable plate 22 is pivotally supported on pins 23. The base plate preferably contains a groove filled with a suitable packing material 24 which seals the joint between the parts. The upper portions of the plates are curved inwardly so that the edges meet, as clearly shown in Figure 10. Along the line of contact a plurality of pairs of perforations in the form of contiguous half circles 25 are provided so as to form circular openings for the sprayer when the movable plate 22 is moved to a closed position. An operating lever 26 is

attached to the movable plate 22 and, as clearly shown in Figure 2, is connected by links 27 and 28 to the foot lever 29.

The movement of the lever 26 governs the size of the discharge openings and controls the force with which the paint is sprayed onto the barrel. Thus if the operator closes the plate 24 tightly the paint will be discharged through the perforations with considerable force but if he close it only partially the flow of paint will be more sluggish. The lever 26 also enables the regulation of the length of time the paint is applied to the barrel, the arrangement shown allowing the operator to stop the flow of paint against the barrel as soon as sufficient coating has been applied, since when the sprayer is opened sufficiently, although the paint will continue to flow from the pump, it will cease to be sprayed against the barrel. During the period between the actual painting of the barrels the sprayer remains open and the paint is allowed to flow over the perforations thus freeing them from any obstructions and keeping them clean.

A driving shaft 30 is rotated by a sprocket wheel 32 and is mounted upon the frame 11 in bearings 31. A frame 33 is suitably disposed over the paint pan 13 and is hinged upon the shaft 30, by bearings 34, the shaft acting as a pivot about which the frame may be swung. The frame supports a pair of shafts 35 upon which are mounted a plurality of wheels 36 which are preferably notched or corrugated in order to give them good contact with the barrel. The shafts 35 are driven by the shaft 30 through the gears 37, the arrangement being such as to allow the free swinging movement of the frame.

The frame 33 constitutes a support upon which the barrel rests while being painted, the wheels 36 operating to rotate the barrel during the painting. It also constitutes a carriage by which the painted barrel is raised from a horizontal to an upright position and deposited upon the guide members 39 and conveyor 38.

The frame 33 is provided with suitable elevating mechanism such as a pair of chains or cables 40 secured to the cable drum 41, and so attached to the carriage 33 that it may be raised and lowered or swung on its pivot. Each cable is preferably fastened to the side of the carriage opposite the pivot side and the cables are guided by upright guide members 42 which keep the cables away from the barrel.

Referring now to Figure 8 it will be seen that the cable drum 41 is carried on a shaft 45 to which it is rigidly secured. The shaft is supported by a pair of the uprights 12 in a bearing 46, and stationary nut bearing 47 which is engaged by a relatively adjustable screw threaded sleeve

48 within which the shaft freely rotates. The sprocket wheel 49 runs idly on the shaft 45 but is held axially in a fixed position against the bearing 46. It carries a clutch member 50 adapted to engage another clutch member 51 which is rigidly attached to the shaft 45.

The engaging screw 48 is operated by a lever 52 by appropriate movements of which the shaft is shifted so that the clutch member 51 is moved into engagement with the cooperating member 50 and thus causes the drum 41 to rotate. The lever 52 also serves to release the clutch when it is desired to stop the rotation of the drum 41. The spring 53 serves to facilitate the disengagement of the clutch members upon a releasing of the clutch. The drum may be provided with guides 54 for the cables 40.

The carriage 33 is provided with an additional cable 55 swung over the pulley 56 and carrying a weight 57. The weighted cable is preferably attached, as illustrated, to that side of the carriage opposite the pivot side and serves as a means of initiating or accelerating the return movement of the carriage from the discharge position to the painting position and serves also as a cushioning or retarding means functioning to diminish the speed and force of the fall during the latter part of the return movement.

Brushes 58 are disposed preferably underneath the barrel and in close proximity to the sprayer 18. To obtain the best results the brushes are arranged to readily adapt themselves to the contour of a barrel and may be placed in staggered formation in order that the brushes may overlap. In the form of construction illustrated each brush is secured to a lever 59 which is pivotally supported upon a rod 60. A weight 61 is placed at the end of each lever 59, opposite from that to which the brush is attached and tends to hold the brush against the surface of the barrel. Thus the brushes are readily adapted to press against the barrels regardless of variations in size, shape and contour. A control rod 62 may be provided by which the depression of the weight side of the levers 59 may be held at a given point in order to save the brushes from unnecessary friction and wear. Thus in painting half barrels, for example, the lower barrel surface will rest at a lower level than is the case when painting larger barrels, and the stop 62 may be moved so as to hold the weighted end of lever 59 at a higher level thus preventing excessive friction on the brushes. In other words, the rod 62 operates to limit or confine the movement of the brushes within certain limits.

As there may be more or less dirt, shavings, sawdust, etc., rubbed off from the barrels during the painting operation a screen 63 may be provided which will tend to keep

the foreign particles on that side of the paint pan opposite the draw-off pipe 14. If desired a horizontally disposed screen may be used to keep the foreign matters from 5 collecting in the paint pan. For example, a screen may be laid over the brush levers 59.

As hereinbefore stated the apparatus is designed to be power operated and in the arrangement illustrated power is supplied 10 to the various parts of the apparatus by the motor 64 which operates the main gear 65 upon the shaft 66. The shaft 66 also carries a sprocket wheel 67 by which power is transmitted through the chain 68 to the sprocket 15 49 which rotates on the shaft 45, the sprocket 32 on the shaft 30 and the sprocket 69 which operates the pump 15.

In operation the barrel to be painted is taken from a suitable runway 70 from the 20 position A and is rolled onto the carriage 33 into position B. The motor is kept running and consequently the barrel is rotated by the wheels 36. The sprayer 18 is normally open in order that the flow of paint 25 may keep it flushed out. But when a barrel is in position for painting the operator closes the sprayer by means of the lever 26 so that the paint is forced out through the perforations 25 and against the surface of the barrel. As the barrel rotates the spray of liquid 30 and the action of the brushes operate to thoroughly coat the barrel surface. The operator then opens the spray pipe so that the paint will cease to strike against the barrel. He may allow the barrel to be rotated for a short time after the spraying has 35 ceased in order that excess paint may be removed from the barrel surface by the brushes 58. He then throws in the clutch 40 by means of lever 52 which causes the drum 41 to rotate and wind up the chain or cable 40. This raises the carriage 33 and elevates the barrel into the discharge or an upright 45 position C as shown in Figure 3. The clutch may then be released with the barrel thus resting upon the discharge skids 39 the 50 weight of the barrel serving to prevent the carriage 33 from dropping back into the painting position B. When, however, the barrel has been removed from the members 55 39 by means of the conveyer 38 the carriage will tend to fall back by gravity. The return movement is given impetus by the weight of the cable 55. At the time that the barrel is in the discharge position C the 60 weight 57 is in position C¹ and it is to be observed that the cable 55 in this instance forms an angle at 56 greater than 45° and consequently upon the removal of the weight of the barrel from the skids 39 the weighted cable exerts a pull on the carriage, the 65 weight 57 descending from position C¹ to position D¹. When the angle made by the cable at 56 has been reduced to about 45° it is obvious that the downward movement

of the weight will cease and that the cable will no longer exert a pulling force upon the carriage 33. As the carriage continues its return movement the angle at 56 decreases and the weight moves upward from position D¹ to position B¹. The weight thus serves to retard the return of the carriage to the painting position B during the latter part of the return movement. By employing the counter weight 57 and cable 55 arranged substantially in the manner indicated so that the weight is caused to initially cause a backward pull on the carriage and so that it acts also to retard the final drop of the carriage to the painting position the speed of the operation is materially increased while at the same time excessive wear of the mechanism is avoided.

In the practice of my invention barrels may be coated or painted thoroughly and at the same time rapidly and with a minimum amount of paint. There is no loss of paint as the operation is carried on over the paint pan and any excess paint sprayed onto the barrel is removed by the brushes and drops into the pan. After being painted the barrel is discharged in an upright position and thus it is not disfigured or soiled by being rolled. The continuity of my system is another distinct advantage inasmuch as the machine may be operated continuously without being interrupted for repairs or cleaning, the arrangement provided for preventing the sprayer from becoming clogged up contributing especially to this desirable result.

It will be obvious to those skilled in the art that various modifications in mechanical structure may be made in the apparatus shown and described in detail herein without departing from the spirit of the invention the scope of which is set forth in the appended claims.

What I claim is:

1. In a barrel painting machine, a paint pan, a sprayer positioned within said pan, means for withdrawing paint from the pan and discharging it through the sprayer, means for supporting a barrel over the paint pan, means for rotating the barrel, brushes adapted to come in contact with the barrel during its rotation, and means for discharging the barrel from the machine in an upright position.

2. In a barrel painting machine, means for rotating a barrel, means for brushing and spraying the barrel while it is being rotated and means for discharging it from the machine in an upright position.

3. In a barrel painting machine, a framework, a paint pan at the base thereof, a movable frame for supporting a barrel over the paint pan, shafts mounted upon the movable frame, wheels adapted to be rotated by said shafts and arranged to rotate the bar-

rel, means for applying paint to the barrel, a power driven shaft geared to the wheel carrying shafts and forming a pivot upon which the movable frame may be swung, elevating mechanism for swinging the movable frame with a hinge movement so as to raise the barrel to an upright position.

4. In a barrel painting machine, means for rotating a barrel while in a substantially horizontal position, means for applying paint thereto, and means for elevating the painted barrel to an upright position.

5. In a barrel painting machine, means for supporting a barrel in a horizontal position, means for rotating same while in said position, means for spraying the barrel, a plurality of brushes automatically adjustable to the contour of the barrel, and means for elevating the barrel into an upright position.

6. In a barrel painting machine, means for applying paint to the barrel, a frame for supporting the barrel in a horizontal position, shafts mounted within said frame, wheels fixed to said shafts and adapted to rotate the barrel; a driven shaft geared to the wheel carrying shafts and upon which the barrel supporting frame is journaled, a cable attached to the frame, a cable drum carrying said cable and means for operating said drum.

7. A barrel painting machine, means for applying paint to the barrel, a frame for supporting the barrel over the paint pan, shafts mounted within said frame, wheels carried by said shafts and adapted to rotate the barrel, a driven shaft geared to the wheel carrying shafts and upon which one side of the barrel supporting frame is loosely mounted, a cable attached to the frame and adapted to swing said frame upon said driven shaft, a cable attached to the frame carrying a counterweight and hung over a pulley.

45 8. In a barrel painting machine, means for applying paint to the barrel, a frame adapted to support the barrel in a substantially horizontal position for painting, shafts mounted within said frame, wheels carried by said shafts and adapted to rotate the barrel, a driven shaft geared to the wheel carrying shafts and upon which the supporting frame is journaled, means for elevating the frame to an upright position by swinging it upon the driven shaft, means for causing the frame to return to the horizontal position.

9. In a barrel painting machine, means for applying paint to the barrel, a frame for supporting the barrel, shafts mounted on said frame, wheels carried by said shafts and adapted to rotate the barrel, a driven shaft geared to the wheel carrying shafts and upon which the barrel supporting frame is journaled, a wheel for driving said shaft, a

drum carrying a cable adapted to raise the supporting frame, a shaft upon which the drum is mounted, a wheel loosely mounted on said shaft, a clutch by which the wheel may be caused to engage the shaft so as to rotate the drum, and a belt for transmitting power to the rotating parts of the mechanism.

10. In a barrel painting machine, a paint pan, means for rotating a barrel in position over said pan, a plurality of brushes automatically adjustable to the contour of a barrel, means for spraying liquid onto the barrel, and means for discharging the barrel in an upright position.

11. In a barrel painting machine, a paint pan, means for rotating a barrel in position over said pan, a rod positioned beneath the barrel, a plurality of levers pivotally mounted upon said rod, a weight on one end and a brush on the other end of each lever whereby the several brushes may be held against the barrel surface, and means for spraying liquid onto the barrel.

12. In a barrel painting machine, a paint pan, means for rotating a barrel in position over said pan, a spray pipe and means for circulating liquid from the paint pan to the spray pipe, a rod positioned beneath the barrel, a plurality of levers pivotally mounted upon said rod, a weight on one end and a brush on the other end of each lever whereby the several brushes may be held against the barrel surface, and means for spraying liquid onto the barrel.

13. In a barrel painting machine, means for rotating a barrel, a rod positioned beneath the barrel, a plurality of levers pivotally mounted upon said rod, a weight on one end and a brush on the other end of each lever whereby the several brushes may be held against the barrel surface, and means for contacting the barrel with liquid.

14. In a barrel painting machine, a paint pan, means for rotating a barrel in position over said pan, a rod positioned beneath the barrel, a plurality of levers pivotally mounted upon said rod, a weight on one end and a brush on the other end of each lever whereby the several brushes may be held against the barrel surface, means for limiting the movement of the brush levers and means for spraying liquid onto the barrel.

15. In a barrel painting machine, means for rotating a barrel, means for applying paint to the barrel, a plurality of brushes so mounted as to be automatically adjustable to the contour of the barrel.

16. In a barrel painting machine, a paint pan, means for rotating a barrel in position above said pan, means for applying paint to the barrel, a plurality of brushes positioned within said pan and so mounted as to be automatically adjustable to the contour of the barrel.

17. In a barrel painting machine, a car-

riage adapted to support a barrel in a substantially horizontal position for painting, means for applying paint to the barrel and means for elevating the carriage so as to raise the barrel to a substantially upright position.

18. In a barrel painting machine, a carriage adapted to support a barrel in a substantially horizontal position for painting, means for applying paint to the barrel, means for moving the carriage so as to raise the barrel to a substantially upright position, and a counterweight arranged and adapted to accelerate the first part of the return movement of the carriage to the painting position and to retard the latter portion of said movement.

19. In a barrel painting machine, a carriage adapted to support a barrel in a substantially horizontal position, means for rotating the barrel in such position, means for applying paint to the barrel while it is being rotated, means for moving the carriage so as to raise the barrel to a substantially upright position and a counterweight in operative connection with carriage in such manner as to give impetus to the first part of the return movement of the carriage to the painting position and to retard the latter part of said movement.

In witness whereof, I have hereunto set my hand this 16th day of November, 1920.

FRED C. FANTZ.
